UNITED STATES PATENT OFFICE.

ABRAHAM NOVICK, OF NEW YORK, N. Y., ASSIGNOR TO UNITED STATES ENVELOPE COMPANY, OF SPRINGFIELD, MASSACHUSETTS, A CORPORATION OF MAINE.

CHIP-REMOVING MECHANISM.

1,290,301.

Specification of Letters Patent.

Patented Jan. 7, 1919.

Application filed July 21, 1917. Serial No. 182,025.

To all whom it may concern:

Be it known that I, ABRAHAM Novick, a citizen of the United States, and a resident of the city of New York, county of Kings, 5 and State of New York, have invented certain new and useful Improvements in Chip-Removing Mechanism, of which the following, together with the accompanying drawings, is a specification.

10 The present invention relates to chip removing mechanism, and in particular has reference to envelop and paper bag machinery, or other machinery of a similar class, where it is desired to remove chips or 15 waste pieces of material which are cut from the web or blank being operated upon. The present application constitutes a continuation of my forfeited application Serial No. 798,236, filed October 30, 1913.

20 The invention resides in the provision of novel means for gripping and separating the partially severed chip from the web or blank which is being operated upon, the invention being herein shown, by way of example, 25 with reference to a continuous web of envelop material, from which envelop blanks are formed by the chip cutting and removing devices hereinafter described. The invention is fully set forth in the following description and particularly pointed out in the annexed claims, reference being had in this connection to the accompanying drawings, in which—

Figure 1 is a fragmentary plan view of 35 mechanism constituting part of an envelop machine, which illustrates my invention.

Fig. 2 is an enlarged vertical section on the line 2—2 of Fig. 1, showing the chip gripping roll in the act of seizing a chip.

40 Fig. 3 is a detached sectional view of said roll in a position advanced a quarter turn from the position shown in Fig. 2.

Fig. 4 is a view similar to Fig. 3, showing said roll in a position advanced a half turn 45 from the position shown in Fig. 2.

Fig. 5 is a perspective view of the chip gripping means employed with said chip gripping roll.

50 Fig. 6 is a perspective view of a cam which is utilized to operate said chip gripping means.

Like reference characters refer to like parts in the different figures.

In the form of my invention herein shown, 55 the side frames 1, 1 have journaled therein

suitable forwarding devices, such as rolls, belts or the like, not shown, for the advancement of a continuous web of material 2, from which, in the present instance, blanks of the desired shape are formed by severance of the web on predetermined lines and by removal of chips or waste therefrom, in the manner hereinafter described. For cutting said chips, the machine provides, in conjunction with the web forwarding devices, not shown, 60 a pair of coöperating rolls 3 and 4, which are carried on shafts 5 and 6 respectively having journaled bearings in the side frames 1, 1. Said shafts have intermeshing gears 7, 7, thereon, one of which is shown in Fig. 1, 70 and one of said gears is driven from a suitable source of power, not shown, whereby the two rolls 3 and 4 are rotated in unison in opposite directions with the web 2 passing between said rolls and traveling in the direction of arrow 75 A, Fig. 2. The roll 3 preferably provides a hardened surface 8, and the roll 4 carries a cutting device 9 which projects outwardly from the periphery of said roll into rolling contact with the hardened surface 8, where- 80 by at each revolution of the roll 4, the web 2 is acted upon by the cutting edges of device 9. As herein shown, said cutting device 9 is so shaped as to make four intersecting incisions in the web 2 at each revolution, as 85 shown at 10, Fig. 1, the chip thus formed being carried along with the advancing web 2, by certain of the fibers of the material which are not completely severed by the cutting operation. It will be understood that 90 chips formed in the center or body of the web, as herein shown, are merely selected for purposes of illustration, since it will be clear that my invention, as hereinafter described, is equally applicable to chips of any 95 character whatsoever, which are formed in any part of a web or blank, or along the edges thereof.

In advance of the cutting rolls 3 and 4 are disposed the chip removing rolls 11 and 12, the same being mounted on shafts 13 and 14 respectively, which are journaled in the side frames 1, 1 and carry intermeshing gears 15, 15, one of the latter being shown in Fig. 1. One of said gears 15 is driven by an 100 idler pinion 16, from the corresponding gear 7 of the cutting rolls, whereby the rolls 11 and 12 are rotated in unison in opposite directions, in the same relation to the web 2 as the rolls 3 and 4. One of said rolls, here 105 110

shown as the lower roll 11, provides a longitudinal slot for the operation of a radially disposed tucker blade 17, the latter being yieldingly held against the rear side of the 5 slot by a compression spring 18, whose force is varied by a screw 19 which enters a recess 20 in said roll and passes loosely through said tucker blade, to hold the same in position. The rotation of roll 11 is so timed

10 as to cause the tucker blade 17 to engage each partially severed chip 10 in the web 2, whereby, owing to the projection of said blade above the periphery of said roll, said chip is deflected away from the surface of 15 the web, as shown in Fig. 2.

Coincident with the deflection of each chip 10 by the tucker blade 17, the rotation of roll 12 brings a slot 21 of said roll directly over the deflected chip, the tucker blade 20 entering said slot 21, as shown in Fig. 2. The roll 12 has journaled therein, adjacent said slot 21, a rock shaft 22, which carries on its outer end a gripper blade 23 for operation within said slot 21. The other 25 end of rock shaft 22 supports a bent arm or lever 24, which projects in opposite directions therefrom. One end of arm 24 has attached thereto a spring 25, whose other end is fixed, as at 26, to the roll 12, the 30 force of said spring being exerted to rock the shaft 22 and carry the blade 23 against the advancing side or wall 27 of slot 21. The other end of arm 24 is carried by the 35 rotation of roll 12 against an interior stationary cam surface 28, whereby the shaft 22 is rocked in the opposite direction to move the blade 23 toward the rear wall 29 of slot 21, in opposition to the force of spring 25. The cam surface 28 is provided 40 by a substantially semi-circular rim or yoke 30, which is secured by screws 31, 31 to one of the side frames 1, said screws preferably extending through elongated slots 32, 32 in said yoke, to permit the latter to be angularly adjusted about the axis of shaft 14.

In the operation of the chip removing mechanism, the parts are so adjusted and timed that the tucker blade 17 deflects the chip 10 upwardly into the slot 21 just in 50 advance of the gripper blade 23, and just before the end of arm 24 drops off of cam surface 28, as shown in Fig. 2. Further rotation of the rolls 11 and 12 causes the release of arm 24 by cam surface 28, whereupon 55 the spring 25 rocks the shaft 22 to carry blade 23 toward its advancing wall 27, the chip 10, which has been tucked into the slot 21 being pinched between said wall and said blade 23 as the tucker blade is carried 60 downwardly out of said slot. The chip 10 is thus separated from the advancing web 2, and carried upwardly and forwardly by the roll 12, as shown in Fig. 3. At an appropriate time, the end of arm 24 is brought again, 65 by the rotation of roll 12, under the influ-

ence of cam surface 28, whereby the blade 23 is moved away from the side or wall 27 of slot 21, and the chip is thereby released, to fall by gravity into any suitable receptacle, not shown, or to be otherwise disposed of. As herein shown, the release of said chip may be caused to occur when the roll 12 is rotated through a half turn, as shown in Fig. 4. In this connection, the suction member 33 may be employed to remove the released chips from the slot 21, as the latter is carried beneath the open mouth of said member. It will be clearly understood, however, that any other chip removing means may be employed, and that the rolls 11 and 12 may have their positions interchanged, so as to bring the chip gripping roll below the web 2, in which case the chip will fall by gravity out of the slot 21.

I claim,

1. The combination with chip cutting means operable on an advancing blank or web, of gripping means comprising two contacting surfaces between which the chip is seized, means for tucking successively cut chips between said gripping surfaces, and means for moving said gripping means to separate the gripped chip from the web or blank.

2. The combination with chip cutting means operable on an advancing blank or web to partially sever a chip therefrom, of gripping means comprising an unyielding surface and a yielding gripper blade coacting with said unyielding surface to seize a chip, a spring to move said blade against unyielding surface, means for separating said gripping surfaces to receive a chip, and means for tucking a chip between said gripping means.

3. The combination, with a pair of rolls having means for cutting a web or blank passing therebetween, of a second pair of rolls having means for removing the chip formed by the cutting operation of said first pair of rolls, said chip removing means comprising a recess in one of said rolls, a yielding tucker blade in the other of said rolls, and a swinging gripper in said recess for engaging the chip.

4. The combination, with cutting means operable on an advancing web or blank, of means for removing the chip produced by said cutting means, comprising a pair of coacting rolls, a swinging chip gripper carried by one of said rolls, a tucker blade carried by the other of said rolls for co-operation with said gripper, and means for actuating said gripper to grip a chip, separate said chip from the web or blank, and release said chip, successively, in the order named.

5. The combination, with cutting means operable on an advancing web or blank, means for removing the chips produced by

- the operation of said cutting means, comprising means for deflecting the chip from the plane of the advancing web or blank, gripping means disposed on the opposite side 5 of the web or blank from said deflecting means, and operable to engage the chip thus deflected, and means for releasing the gripped chip from the gripping means at a point removed from the plane of said web or 10 blank.
6. The combination, with cutting means operable on an advancing web or blank, of means for removing the chips produced in said web or blank by the operation of said 15 cutting means, comprising a pair of coacting rolls, one on each side of said advancing web or blank, gripping means carried by one of said rolls, means carried by the other of said rolls for deflecting a chip into the path of 20 said gripping means, and means for actuating said gripping means to seize said chip, whereby the latter is separated from the web or blank by the rotation of the said first mentioned roll.
- 25 7. The combination, with means for cutting chips from an advancing web or blank, of a pair of coacting rolls, a tucker blade yieldingly mounted in one of said rolls, a rock shaft loosely journaled in the other 30 of said rolls, a gripper blade attached to said rock shaft, means for rotating said rolls
- in unison, whereby the tucker blade deflects a chip into the path of the gripper blade, means for operating said rock shaft to cause 35 said gripper blade to grip said chip, whereby said chip is separated from the web or blank on the further rotation of said rolls, and means for operating said rock shaft to release said chip from said gripper blade.
8. In a device for gripping and separating 40 chips from an advancing web or blank, a revolute roll, a tucker blade yieldingly mounted in said roll, a revolute slotted roll coacting with said first mentioned roll, a rock shaft loosely journaled in said slotted roll, 45 a gripper blade attached to said rock shaft, means for rotating said rolls in unison, whereby said tucker blade deflects a chip into the path of said gripper blade, means for operating said rock shaft to cause said 50 gripper blade to coact with the reentrant surfaces of said slotted roll to grip said chip, whereby said chip is separated from said web or blank on the further rotation of said rolls, and means for operating said rock 55 shaft to release said chip from said gripper blade.

Dated this 18th day of July, 1917.
ABRAHAM NOVICK.
